UNITED STATES PATENT OFFICE.

ALBERT T. FISCHER, OF CLEVELAND, OHIO.

TRANSPARENT SIGN.

968,459.

Specification of Letters Patent. Patented Aug. 23. 1910.

Application filed September 7, 1909. Serial No. 516,635.

To all whom it may concern:

Be it known that I, ALBERT T. FISCHER, citizen of the United States, residing at Cleveland, in the county of Cuyahoga and 5 State of Ohio, have invented certain new and useful Improvements in Transparent Signs, of which the following is a specification.

My invention has reference to transparent signs, and the invention consists in a sign having the transparent portion thereof printed upon both sides of a sheet of paper or equivalent transparent or translucent material and surrounded by a dark or 15 opaque contrasting background. The sign or relatively transparent portion proper may consist in letters, numerals, fanciful or practical designs of any kind or character, figures or pictures of various objects and 20 whatever may be preferred to represent in this way and in varying colors, shades and tints, the range of possibilities in these particulars being practically unlimited and as wide as the printers' art. With it all, however, 25 there is necessarily present a practically dark or non-transparent field or background to give contrast and full expression to the design, and the invention resides in a sign having the character or picture or 30 whatever the object may be displayed by printing alike upon both sides and on a single sheet of paper or other material which in itself is transparent and has such characters or pictures developed thereon in relatively 35 transparent colors, or blank in the body of the sign, but with the body or surrounding portion of the paper covered with ink or other darkening substance to give the desired relief to the picture.

Reference should be had to the accompanying drawing in which—

Figure 1 is the front elevation of a portion of a sign embodying my invention; and Fig. 2 is a rear elevation of the showing in 45 Fig. 1.

For the purpose of illustrating one embodiment of my invention I have shown in the drawing a sign in which the body 1 is of relatively transparent material, upon which 50 the sign characters indicated at 10, 11 are preferably printed in relatively transparent colors or shades, while the portion of the back-ground 8, 9 immediately surrounding the characters is quite dark for the purpose 55 of giving contrast and expression to the design. A lighter tint or shade of the same

color or a different color may form an auxiliary back-ground as shown in 2, 4 while the whole may be framed by a marginal portion 5, 7, and border strips 3, 6 of any desired shades, tints or colors. To make a sign of this kind the utmost possible exactness needs to be practiced in order that all the finer lines of the picture shall be preserved, because when viewed from either side the picture must have the perfect outlines of a single clean imprint, and any lack of exactness in producing the picture or which would mar or blur the outlines would defeat the invention. Hence I prefer to employ an exact working printing press for 60 this purpose, say one that has a reciprocating bed adapted to carry a printing form and a revolving or oscillating cylinder to run over the same to make the desired impression. The ordinary method of printing is not, however, to be followed in this case. On the contrary, I require the cylinder to 65 perform a double function instead of only one as heretofore. Thus, having a form for 70 the sign in proper position on the bed of the machine I first ink the same as usual and then take an impression therefrom directly upon the cylinder. Then I introduce the 75 paper or material to be printed upon and imprint the same upon both sides simultaneously, or from said form on one side and from said cylinder on the other side. Obviously the most exact registration of 80 cylinder and form are required in this 85 operation, and the product is a clean cut picture practically printed through the paper and exactly alike on both sides. The 90 background is printed on both sides in the same operation and in the sign is completed 95 by two opposed impressions applied at the same time.

The foregoing outline as to a practical method of producing a transparent sign according to my invention constitutes also my present preferred method but does not bar the use of others, but in any event it does 100 practically exclude running the paper through a machine the old way and printing on one side at a time and then on the other. The measure of exactness required 105 in the delicate outlines of a transparent picture printed on both sides would seem to render any process of successive or progressive printing impracticable.

As above indicated, I begin with a relatively transparent material, necessarily. In 110

some cases I may cover this with my form in such way as to work outlines of characters, such as letters or figures and designs of different kinds directly upon the surface 5 of the material and only print the background around the same. Then the plain or uncolored portions would represent the sign. This in a true sense also would be by printing because the transparent figures or 10 characters would be according to the form from which such printing was done, or in other words it is negative work, but entirely practical according to my invention.

What I claim as new and desire to secure 15 by Letters Patent is:

1. In a sign, a body of relatively transparent material, a coating substance applied by printing to one side of said body so as to form a positive impression of the background 20 of the sign, and a coating substance, applied by printing to the reverse side of the body so as to form a negative impression of the background of the sign, the two 25 coatings being so positioned that the background is formed in every part of a double thickness of said substances, whereby the sign characters are caused to appear by the contrast of the light passing through the sign characters with the light passing 30 through the background.

2. In a sign, a body of relatively transparent material, a coating applied by printing to one side of the body so as to form a positive impression of the sign characters 35 and of the background therefor, and a coating applied by printing to the reverse side

of the body so as to form a negative impression of the sign characters and of the background therefor, the sign characters and the background being printed in coloring materials of different degrees of transparency 40 and the two coatings being so positioned on the body as to cause the characters on the opposite sides to fully register, whereby the sign characters are caused to appear by the 45 contrast of the light passing through them with the light passing through the background.

3. In a sign, a body of thin, flexible and relatively transparent material, a coating applied by printing on one side of the body so as to form a positive impression of the sign characters and of the background therefor, and a coating applied by printing on the reverse side of the body so as to form 50 a negative impression of the sign characters and of the background therefor, the sign characters and the background being printed in inks of different degrees of transparency 55 and the two coatings being so positioned on the body as to cause the characters on the opposite sides to fully register, whereby the sign characters are caused to appear by the contrast of the light passing through them with the light passing through the background. 60

In testimony whereof I affix my signature in presence of two witnesses.

ALBERT T. FISCHER.
